UNITED STATES PATENT OFFICE.

ARTHUR SIMON, OF MILWAUKEE, WISCONSIN, ASSIGNOR TO THE CUTLER-HAMMER MFG. CO., OF MILWAUKEE, WISCONSIN, A CORPORATION OF WISCONSIN.

FLUID-RHEOSTAT.

1,112,165.

Specification of Letters Patent. Patented Sept. 29, 1914.

Application filed March 10, 1913. Serial No. 753,303.

To all whom it may concern:

Be it known that I, ARTHUR SIMON, a citizen of the United States, residing at Milwaukee, in the county of Milwaukee and 5 State of Wisconsin, have invented new and useful Improvements in Fluid-Rheostats, of which the following is a full, clear, concise, and exact description, reference being had to the accompanying drawing, forming a 10 part of this specification.

My invention relates to fluid rheostats.

It has among its objects to provide means for improving the circulation of fluid through rheostat tank; to provide improved 15 means for varying the fluid level, and to provide an improved electrode construction.

Other objects and advantages of my invention will hereinafter appear.

For the purpose of more fully and clearly 20 disclosing the nature and advantages of my invention I shall describe the rheostat illustrated in the accompanying drawing, it, of course, being understood that the drawing is not to be considered as unnecessarily limiting the scope of the appended claims.

In the accompanying drawings, Figure 1 is 25 a top plan view of the rheostat; Fig. 2 is a vertical sectional view on line 2—2, Fig. 1; and Fig. 3 is a transverse sectional view 30 on line 3—3, Fig. 1.

The rheostat includes an electrode tank 5 substantially rectangular in form and superimposed upon an overflow tank 6 of suitable construction. As illustrated, there are 35 four electrodes 7, 8, 9 and 10 suspended in the tank 5. These electrodes are preferably arranged to extend longitudinally of the tank and in a parallel relation to one another. In practice, they may be of various 40 different constructions but are preferably constructed as hereinafter described. The resistance fluid is fed into the tank 5 through an inlet 11 at one end thereof and discharged at the opposite end of said tank 45 into the tank 6. The fluid may then be withdrawn from a port 12 in the tank 6 and again supplied to the tank 5. This circulation of the fluid may be readily accomplished by a centrifugal pump 13 connected 50 between the two tanks.

In practice the variation of the resistance of the rheostat is preferably accomplished by varying the level of fluid in the tank 5 with respect to the electrodes. Further it is 55 very desirable in practice to provide for a

circulation of the fluid throughout the entire operative period of the rheostat. This is desired to prevent overheating and the consequent formation of gases.

The tank illustrated embodies means 60 which I shall now describe that provides for a most efficient regulation of the level of the fluid and also a most advantageous circulation of the fluid. This means includes a vertical weir 14 located at the end 65 of the tank adjacent to the intake 11 and extending the entire width of the tank and to a height corresponding to the highest fluid level desired. It further comprises an outlet at the opposite end of the tank preferably 70 in the form of a transversely extending opening 15 in the bottom of the tank, said opening extending the entire width of the tank and having a slide 16 for closing the same to any desired degree. With this arrangement it will be apparent that all fluid 75 entering the tank must pass over the upper edge of the weir or partition 14 which, being level, causes the fluid to be equally distributed across the entire width of the tank 80 whereby it will pass the electrodes in uniform parallel streams. Also, since the outlet extends the entire width of the tank, this uniformity will be maintained until the fluid leaves the tank. A most efficient circulation 85 is thereby provided. It is sometimes desirable to provide for retention of a certain amount of fluid in the tank corresponding to the maximum resistance desired and to this end the portion of the bottom of the 90 tank containing the outlet is preferably elevated from the main portion 17 of the bottom to a degree corresponding to the amount of fluid to be retained. Under some conditions it might be desirable to entirely 95 close the outlet 15 and yet maintain the circulation of fluid in the tank. To permit this, I preferably provide, at the outlet end of the tank, an overflow weir 18 similar to the weir 14 at the intake end of the tank. 100 The overflow opening back of the weir 18, and also the outlet 15, communicate with the tank 6. The slide 16, by adjusting the size of the outlet 15, enables the level of the fluid in the tank 5 to be regulated at will. Assuming that the fluid is supplied to the tank 105 at a constant rate, it is obvious that the level of the fluid may be raised by adjustment of said slide to restrict the outlet 15 and may be lowered by adjustment of the 110

slide in a reverse manner. The slide 16 may be arranged to be operated in any suitable manner but in practice I prefer to mount the same on the end of a lever or a pair of levers 19 fulcrumed adjacent to the upper edge of the tank 5 to a pin or rod 20 supported by the walls of said tank. Further, I prefer to provide the lever or levers 19 with a bell-crank arm 21 and connect the free end of said arm through a suitable link 22 to a crank shaft 23. This enables adjustment of the slide 16 by operation of said crank shaft, which operation may either be performed manually or by a motor 24 through suitable gearing 25. This provides a very simple but efficient means for adjusting the slide 16 and accordingly varying the level of fluid in the tank for securing the desired resistance regulation.

20 The electrodes are preferably of the construction illustrated in Fig. 3. As here illustrated, each electrode comprises a sheet of metal 30 folded to form a hollow member tapered in cross section, the ends of the plate being secured to a supporting member 31. This construction of electrode has two distinct advantages. It enables the circulation of fluid through the electrode and the utilization of such fluid for cooling purposes exclusively. Further, when a number of such electrodes are assembled in the manner illustrated, the distance between the same gradually decreases from the bottom of the tank upwardly. Thus their construction assists in the decrease of resistance as the fluid in the tank rises and thereby provides for a greater reduction in the resistance than could be obtained by mere variation in the fluid level if the electrodes were spaced uniformly throughout.

40 The electrodes may be supported in the tank in any suitable manner. As illustrated, they are supported by engagement of the ends of their supports 31 with insulating devices 32 secured to plates 33 extending across the top of the tank 5 at opposite ends thereof.

50 The electrodes may be connected in circuit in any preferred manner in accordance with the functions to be performed thereby. As illustrated, the electrodes 7, 8 and 9 are provided with terminals 34, 35 and 36 respectively, while the opposite end of the electrode 7 is electrically connected by a metallic strip 37 to one end of the electrode 10.

60 The rheostat illustrated is adapted for either intermittent or continuous duty but where used for continuous duty it might be desirable to provide some of the numerous well-known means for cooling the fluid in its passage from the tank 6 to the tank 5.

What I claim as new and desire to secure by Letters Patent is:

65 1. In a fluid rheostat, a tank, electrodes

therein, said tank having a fluid inlet, and means insuring a uniform distribution of the fluid throughout the entire width of the tank as it passes to said electrodes.

2. In a fluid rheostat, a tank, electrodes 70 therein, said tank having a fluid inlet, and means insuring a uniform distribution of the fluid throughout the entire width of the tank as it passes to said electrodes, said electrodes being disposed parallel to the 75 current of the fluid.

3. In a fluid rheostat, a tank having an inlet at one end thereof, electrodes mounted in said tank, and a weir between said inlet and said electrodes extending the entire 80 width of said tank.

4. In a fluid rheostat, a tank having an inlet at one end thereof, electrodes mounted in said tank, and a weir between said inlet and said electrodes extending the entire 85 width of said tank, said electrodes being substantially at right angles to said weir.

5. In a fluid rheostat, a tank provided at one end with an inlet, and means insuring a uniform distribution of the fluid throughout the entire width of the tank, said tank being provided at its opposite end with an outlet extending the entire width of the 90 same.

6. In a fluid rheostat, a tank provided at 95 one end with a fluid inlet, and means insuring a uniform distribution of the inflowing fluid throughout the entire width thereof, said tank being provided at its opposite end with an adjustable outlet extending across 100 the bottom thereof and with an overflow opening separated from said outlet by a weir extending the entire width of the same.

7. In a fluid rheostat, a tank provided at one end with an inlet and with a weir adjacent to said inlet extending the entire width of said tank and at its opposite end with an overflow weir parallel to said first mentioned weir and between said weirs with an overflow opening extending the entire 110 width thereof and parallel with said weirs.

8. In a fluid rheostat, a fluid tank, a second tank superimposed upon the same, electrodes in said second tank, means for circulating the fluid through both of said 115 tanks, said electrode tank having adjacent to one end of said electrodes means for insuring a delivery of fluid uniformly thereto from the maximum fluid level.

9. In a fluid rheostat, a fluid tank, a 120 second tank superimposed upon the same, electrodes in said second tank, means for circulating the fluid through both of said tanks, said electrode tank having adjacent to one end of said electrodes means for insuring a delivery of fluid uniformly thereto from the maximum fluid level and having an outlet in its bottom extending the entire 125 width thereof and at right angles to the flow of fluid.

10. In a fluid rheostat, a tank having fluid inlet and outlet ports at opposite ends thereof and electrodes within said tank between said ports, said electrodes being hollow and open-ended and disposed with their open ends contiguous to said ports.

11. In a fluid rheostat, a tank having means for varying the fluid level therein and electrodes in said tank, each of said electrodes having its faces of maximum area angularly disposed with respect to one another to converge toward the bottom of said tank.

12. In a fluid rheostat, a fluid tank having inlets and outlets at opposite ends thereof, means for varying the level of fluid therein, and hollow electrodes having open ends contiguous to the inlet and outlet ends of said tank and having their sides tapering toward the bottom of said tank.

13. In a fluid rheostat, a fluid tank and electrodes therein arranged in a parallel re-

lation, said electrodes comprising sheet metal plates folded to form hollow members tapering toward the bottom of said tank.

25

14. In a fluid rheostat, a tank provided with an elongated outlet opening, a pivoted member for restricting the size of said opening, a crank and an operative connection between said crank and said pivoted member.

30

15. In a fluid rheostat, a tank provided with an outlet slot in the bottom thereof, a plate movable along the bottom of said tank to restrict the size of said slot, a lever supporting said plate, a crank and an operative connection between said crank and said lever.

35

In witness whereof, I have hereunto subscribed my name in the presence of two witnesses.

ARTHUR SIMON.
